UNITED STATES PATENT OFFICE.

ALFRED S. HENN AND GEORGE H. JENNINGS, OF NEW HAVEN, CONN.

POOL-RACK.

SPECIFICATION forming part of Letters Patent No. 255,625, dated March 28, 1882.

Application filed February 1, 1882. (No model.)

To all whom it may concern:

Be it known that we, ALFRED S. HENN and GEORGE H. JENNINGS, of New Haven, in the county of New Haven and State of Connecticut, 5 have invented a new Improvement in Pool-Racks; and we do hereby declare the following, when taken in connection with accompanying drawings and the letters of reference marked thereon, to be a full, clear, and exact 10 description of the same, and which said drawings constitute part of this specification, and represent, in—

Figure 1, a front view; Fig. 2, a longitudinal sectional view; Fig. 3, a partial transverse section; Fig. 4, a vertical section, showing the stop to arrest the balls at the end of the pockets.

This invention relates to an improvement in the receiver usually hung upon the wall of a room where the game of pool is played, to receive the balls, and thereby record the count, 20 commonly called "pool-racks." This game is usually played by several persons, and the game is of short duration. Hence in pool-rooms where there are numerous tables it is necessary that some person in charge shall keep a 25 watch over the game in order to record the number of games and to see that no deception is practiced by the players, the pay for the use of the table being at a certain price per game. 30 In the usual construction the balls may be introduced or removed therefrom at pleasure and returned to the table in order to prolong the game.

The object of this invention is to construct 35 the rack to receive the balls and retain them, so that they cannot be removed without making a registration of such removal; and it consists in a rack to receive the balls arranged in a case, and so as to be moved longitudinally 40 therein, with apertures for the introduction of the balls to their respective channels in the rack, and arranged so that after the balls have once entered their channels they cannot be removed except by longitudinal movement of the 45 rack, and also in combining with such a rack a registering mechanism which will record the number of times the rack is thus moved to take the balls therefrom, and as more fully hereinafter described.

50 The rack consists of several bars, A B C, and may be of substantially the usual form. They

are arranged in a case, D, provided with a front, E, which by preference is hinged to the case, and should be open, so as to expose the balls as they lie in their channels, the openings F in the door being narrower than the diameter of the balls. At one end of the case several openings, 1 2 3, are made, each corresponding to one of the channels, and of sufficient diameter to receive the balls. Hence, 55 when a ball is placed through either of the openings—say 2—it passes directly into the channel, the bars being inclined for that purpose, as in the usual construction of rack.

A stop is provided to arrest the progress of 60 the balls when they shall have arrived at the end of the exposed part of the channel. This stop consists of a vertical bar, a, arranged in the case, with a spring, b, at the bottom, the tendency of which is to force the bar upward. 70 From the bar an arm, d, extends forward and is turned up through a slot, e, in the bars of the rack, as seen in Fig. 4, so as to stand in the path of the balls and arrest them, as seen in Fig. 2, when they shall have arrived near 75 the end of the opening in the front. A stop is also provided to prevent the balls from being moved back through the channel to the mouth through which they are inserted. These stops consist of several tongues, f, hinged upon the 80 under side of the bars, as seen in Fig. 2, which turn up to permit the balls to enter, then fall back against a stop, h, which arrests them in a vertical position, and so as to prevent the possibility of the ball being returned to the 85 mouth through which it entered.

The rack is free for longitudinal movement in its case, as from the position seen in Fig. 2 to that in broken lines, same figure. In such movement of the rack a trip, i, on the rack 90 strikes an inclined foot, m, on the bar a and forces it downward, so as to draw the stops d downward and out of the way of the balls, so that the balls then are free to move to the extreme end of the rack, that extreme end of the 95 rack at such time being outside the case, as indicated in broken lines, Fig. 2, the balls being readily taken therefrom. While the rack thus stands open for the discharge of the balls the other end is closed by the end of the rack 100 passing the openings 1 2 3, through which the balls were inserted. After the balls have been

removed the rack is returned into the case, and is then set for a new game.

The rack may be locked in its case, so that only the person in charge can move it. Hence 5 by attending to the rack he knows how many games are played without other information than that given by the call upon him to remove the balls.

To prevent the change of balls from one bar 10 to another, stops *n*, like the stops *f*, are provided at the discharge end of the rack, which permit the balls to pass out from the pockets at that end, but prevent their being returned.

In order that the rack may be cleared at the 15 end of each game without the necessary attention of the person in charge, we apply a registering apparatus which will make a record whenever the rack is moved. This registering apparatus consists of a ratchet-wheel, 20 *L*, arranged at a convenient point on the case, and a spring-pawl, *r*, on the rack, which will pass the teeth in the ratchet when it is thrown outward for the removal of the balls, but on being returned will engage the teeth on the 25 wheel and return it one point. In connection with this wheel *L* is a dial, as seen in Fig. 1, or it may be a pointer rotating on a dial, so that each time the wheel is turned it will be indicated on the dial. A stop-pawl, *s*, is arranged 30 to prevent the return of the wheel.

Any registering apparatus which may be operated by the movement of the rack may be arranged to record such movement of the rack. The front should be hinged, so that should a 35 mistake occur in the introduction of a ball into the wrong pocket a correction may be made by the person in charge, he simply opening the door and making the correction, then closing the door and locking it.

40 We claim—

1. The combination of several bars, A B C, arranged in the form of a rack and in a case, within which it is made longitudinally movable, corresponding openings in the case for 45 the insertion of the balls to the respective pockets or bars of the rack, the longitudinal movement of the rack within the case opening the several pockets for the removal of the balls, substantially as described.

50 2. The combination of several bars, A B C, arranged in the form of a rack and in a case, within which it is made longitudinally mov-

able, corresponding openings in the case for the insertion of the balls to the respective pockets or bars of the rack, the longitudinal 55 movement of the rack within the case opening the several pockets for the removal of the balls, and a stop to prevent the return of the balls from the rack to the mouth through which they are inserted, substantially as described.

3. The combination of several bars, A B C, arranged in the form of a rack and in a case, within which it is made longitudinally movable, corresponding openings in the case for 60 the insertion of the balls to the respective pockets or bars of the rack, the longitudinal movement of the rack within the case opening the several pockets for the removal of the balls, and a stop to arrest the balls on the 70 rack and prevent their passing to the discharge-openings, with a trip on the rack to remove the said stop when the rack is moved for the discharge of the balls, substantially as described.

75 4. The combination of several bars, A B C, arranged in the form of a rack and in a case, within which it is made longitudinally movable, corresponding openings in the case for 80 the insertion of the balls to the respective pockets or bars of the rack, the longitudinal movement of the rack within the case opening the several pockets for the removal of the balls, and a stop, *n*, arranged to permit the balls to pass out from the pockets when opened, 85 but prevent their return, substantially as described.

5. The combination of several bars, A B C, arranged in the form of a rack and in a case, within which it is made longitudinally movable, corresponding openings in the case for 90 the insertion of the balls to the respective pockets or bars of the rack, the longitudinal movement of the rack within the case opening the several pockets for the removal of the 95 balls, and a registering mechanism, substantially such as described, to record each longitudinal movement of the rack, substantially as described.
